WESLEY E. WHELESS, OF SHREVEPORT, LOUISIANA, ASSIGNOR TO ALLEN MANUFACTURING COMPANY, OF SHREVEPORT, LOUISIANA

PACKAGE FOR KNOCKED-DOWN WINDOW-SCREEN FRAMES

Application filed June 8, 1929. Serial No. 369,417.

This invention relates to window screen frames, and more particularly to the manner of packaging the same in a knocked down or collapsed condition.

5 The principal object is to provide a package which is uniform in size and shape, which avoids all unnecessary bulkiness, which is convenient to handle and yet contains all the essential parts of a window screen frame in 10 a knocked down condition.

Heretofore, the shipping of window screen frames has resulted in great damage to the frames due to breakage resulting from rough handling, and the frailty of the frame. Further, the frames occupied a large amount of 15 space in transportation.

I conceived the idea of shipping the screen frames in knocked down condition, so that the individual could re-assemble the frame 20 with a very little trouble.

The parts of the screen are machined to fit so that it is only necessary for the individual to fit the parts together.

I was next confronted with the problem 25 of designing a proper package for shipping the parts of the frame. I wanted the package to be compact and of uniform thickness so as to present as few projections as possible to prevent the bursting of the package which often occurs in shipping where there are 30 projections.

I found that there would be two sets of parts, and the respective members in each part would be of substantially the same 35 length. It, therefore, became essential to divide the parts into two packages for the sake of compactness. It was further desirable that the two packages be of the same thickness.

40 My problem was to design the parts so that although the parts as used in the frame would be of varying width, the two packages would present the same thickness when 45 wrapped for shipment.

In the drawings:

Figure 1 is a front view of the assembled screen in perspective;

50 Figure 2 is a perspective of the frame in partly knocked down condition;

Figure 3 is a perspective of the frame wrapped for shipment; and

Figure 4 is a section along the line 4—4 of Figure 3.

Referring to the drawings, in which like numerals designate similar parts,

Numeral 1 designates a screen frame having side pieces 2, top piece 3, middle piece 4, and bottom piece 3'. The side pieces 2 have slots 5 in their ends to receive tongues 6 at the ends of the top and bottom piece 3 and 3' respectively. The middle of the side pieces 2 having recesses 7 to receive the tongues 8 at the ends of the middle piece 4. Screening 9 is placed on the frame 1 (as 65 shown in Figure 1), and strips 10 are placed on top of the screening and secured to the frame 1 by brads 11.

A covering of paper 12 (as shown in Figure 3) forms the package 13 and a covering 70 of paper 14 forms a second package 15. Strips of re-enforcing paper 16 encase the ends of the packages 13 and 15 and strips 17 form hinges to connect the packages 13 and 15 together.

In order to get uniform thickness, the side pieces 2 are placed in package 13 in upright position with the two corresponding strips 10 placed between the side pieces 2 in the same relative position.

The package 15 is formed by placing flat on the bottom the bottom piece 3', and on top of it, the three strips 10 in the same relative position, which, when placed side by side, are of the same width as the bottom piece 3'. On top of the three strips 10 are placed the top piece 3 and middle piece 4, side by side. These two pieces when thus arranged, are of the same width as the bottom piece 3', and the package is of the same 90 height as the package 13.

In unwrapping, the strips 17, which encircle the two packages 13 and 15 during shipment, may be separated at the point of separation between the two packages, and the paper 12 and 14 unrolled from the respective packages without becoming entirely separated, as the strips of paper 17 on the opposite side from the side open will serve to form connecting hinges.

What I claim is:

1. A package for shipping knocked-down screen frames of that type, the width dimension of whose long pieces is so designed with respect to the thickness dimensions of whose short pieces that the aggregate thickness of a number of the short pieces equals the width dimension of the long pieces, said package comprising two parts in which the long and short pieces are separately stacked, the long pieces being arranged with their width dimension forming one dimension of the package and the short pieces being adjacently arranged, with their width dimensions perpendicular to the width dimension of the long pieces, and stacked to the same height as the width dimension of the long pieces, said parts being secured together to form a single package.
2. A package for shipping knocked-down screen frames of that type, the width dimension of whose long pieces is so designed with respect to the thickness dimensions of whose short pieces that the aggregate thickness of a number of the short pieces equals the width dimension of the long pieces, said package comprising two parts in which the long and short pieces are separately stacked, the long pieces being arranged with their width dimension forming one dimension of the package and the short pieces being adjacently arranged, with their width dimensions perpendicular to the width dimension of the long pieces, and stacked to the same height as the width dimension of the long pieces, and means for uniting said parts into a single package, said means being constructed to form a hinge when said package is opened.

In testimony whereof I affix my signature.
